Patented Oct. 5, 1926.

UNITED STATES PATENT OFFICE.

REPORT R. VAN SANT, OF PEORIA, ILLINOIS.

FUEL-BURNING SYSTEM.

Application filed May 4, 1925. Serial No. 27,643.

This invention has reference to a liquid fuel burning system designed preferably for heating purposes in homes, dwellings or commercial buildings, and it is to be understood that it may be employed in any similar capacity wherein liquid fuel is carried from a source of supply to a point of consumption. Such a system may use any of the well known combustibles, such as fuel oil, kerosene, gasoline, distillate or gas oil.

The invention has for one of its objects to provide in a liquid fuel burning system a safety controlling means adapted to determine the level at which the liquid fuel will rise when filling the fuel reservoir or container and to prevent the same from overflowing into the fuel system.

The invention has for a further object to provide in a liquid fuel burning system including supply and return fuel lines and an air line in communication with the supply line, a reserve fuel tank in communication with both the fuel supply and air lines which functions on the starting of the pump to act upon the air, to create the suction, to pull the fuel from the source of supply into the supply line, and upon the cessation of the pump to act as a reservoir to receive excess fuel in the supply line between the tank and the source of supply to cause the air in the air line to break the siphon in the supply fuel line.

That the invention may be more fully understood, reference is had to the accompanying drawings, illustrating a preferred embodiment of the invention and forming a part of this description, in which:—

Figure 1 is a greatly reduced side elevation and a more or less diagrammatic view, partly in section, showing a fuel burning system embodying my invention;

Figure 2 is a cross-sectional view of my safety controlling means connected with the fuel reservoir or container;

Figure 3 is a top plan view showing a cross-bar, a part of the safety controlling means, taken on the line 2—2, Figure 2, and

Figure 4 is a view of the reserve fuel tank having communication with the fuel and air supply line, similar to that disclosed in Figure 1, except that the liquid fuel is shown at the level the fuel assumes when the pump is in operation.

Like characters of reference denote corresponding parts throughout the figures.

The liquid fuel burning system disclosed herein is not unlike the fuel systems now in general use, and includes the usual fuel reservoir or container located preferably underground and at a distance from the burner or heater usually found in the basement of a home or building. It is possible, however, that the fuel reservoir or container may be located within the building or dwelling and at close proximity to the burner or heater. The pump shown to supply the liquid fuel from the source of supply to the burner or heater is of a well known type and provides a suction on the supply side and a pressure on the discharge side, as will be understood, the unused portion of liquid fuel being returned under pressure to the fuel reservoir or container.

There has been no attempt made to show the detailed construction of the burner or its operating parts, except the general outline of the pump and atomizer controlling the ejection of the fuel in the furnace, shown in dotted lines, and it is to be understood that the invention is capable of operation with any of the well known types of fuel burners or grades of fuel.

In the drawings, a fuel reservoir or container 1 is shown preferably located underneath the ground and within an enclosure 2. An air supply vent or pipe 3 is attached near the top of the reservoir or container 1 and is shown having communication with the outside atmosphere for the ingress and egress of air into the reservoir or container 1, for purposes well understood.

Connected with the top of the reservoir or container 1 in a similar manner to the air vent or pipe 3, is a safety controlling means 4, to be described more in detail, and which includes a filling pipe 5 extending from the enclosure 2 and above the ground, into which the liquid fuel is poured to fill or replenish the reservoir or container 1.

Depending within the fuel reservoir or container 1 to within a short distance of the bottom thereof is a fuel supply line or pipe 6 which extends upwardly from the outside of the reservoir 1 preferably at or near an even elevation to the safety controlling means 4, where by means of an L 7 the supply line 6 takes preferably a horizontal direction out through the enclosure 2, into the ground 8 and through the wall of the building or dwelling 9 and by means of a T 10

communicates with an upstanding pipe or line 6' within the building or dwelling.

By means of a T 11 including a plug 12 for draining purposes, and a nipple 13, the pipe or line 6' is connected to an upstanding reserve fuel tank 14 at or near the lower end thereof. Leading from the bottom of the tank 14 a supply pipe or line 6'' is shown directed beneath the basement floor 15 to a point near the furnace and again directed upwardly where it is intercepted by a globe valve 16 intended to be used for either regulating the flow of fuel through the supply fuel line or to close the same for repairs in the system. The fuel pipe or line 6'' extending upwardly from the valve 16 is shown intercepted by a union 17 and a filter 18 of any well known type or design intended to filter or strain the liquid fuel in its passage from the reservoir 1 to the pump 19. It will be understood that with the pump 19 in operation, the liquid fuel is caused to pass through the supply line 6, 6' and 6'' and the connections identified to the pump 19 by reason of the suction created by said pump in said line. The supply line 6'' is continued on from the pump 19 by means of suitable connections and through the medium of a valve 20 the liquid fuel is caused to pass through a small pipe or line 21 which has an entrance into the furnace or heater 22, shown in dotted lines. It will be understood, that the valve 20 is a regulating valve intended to regulate or control the passage of fuel into the small pipe or line 21 and the atomizer, not shown, inside the furnace or heater 22.

Leading from the valve 20 in a downwardly direction, a return fuel pipe or line 23 having a union 24 and a globe valve 25 included therein for purposes previously explained in connection with corresponding parts 17 and 16, respectively in the supply line, is directed beneath the basement floor 15 in a similar manner to the supply line or pipe 6'' and follows its general direction and is directed upwardly by means of an L 26 again within the building or dwelling and by means of an L 27 leads out through the building wall 9, the earth 8 and enclosure 2, where by means of suitable connections, it is suitably connected to the fuel reservoir or container 1. It will be further understood, that with the pump 19 in operation, the unused or excess liquid fuel is caused to return to the reservoir or container 1 under a slight pressure through the return fuel line or pipe 23.

Leading preferably upwardly from the T 10 connected to the supply line an air pipe or line 28 is attached and by means of the L's 29 and 30 assumes preferably a parallel relationship with the supply fuel line 6' and by suitable means is connected to the upstanding reserve fuel tank 14, previously referred to.

The reserve fuel tank 14 is preferably of the cylindrical type and has included in a side wall thereof a gooseneck connection 31 provided with a plug 32 for priming and filling purposes. The connection 31 is located in the side wall thereof preferably at an elevation above the middle portion thereof in order that the tank may be filled with a reasonable amount of liquid fuel for purposes to be later described.

In Figure 2 the safety controlling means 4, previously referred to, is shown in detail including a tubular shell or casing 4' and being supported by suitable connections at its lower end which have connection with the top wall of the reservoir or container 1. In the upper neck of the shell or casing 4' is provided a tapered seat 33 into which is seated a cone valve 34 forming the uppermost portion of an elongated tubular float 35 located within the shell or casing 4'. The float 35 in open position rests on a skeleton cross-bar 36 located in the connection to the reservoir or container 1. The peculiar construction of the skeleton cross-bar 36 is adapted to serve a two fold purpose and it will be understood that besides serving as a support for the float 35 allows liquid fuel to flow between the float 35 and shell or casing 4' and down into the reservoir or container 1. It will be understood, that upon pouring liquid fuel into the filling pipe 5, the fuel will enter the shell or casing 4', flow down between the float 35 and said shell or casing past the skeleton cross-bar 36 and into the reservoir or container 1. It will be further understood, that upon the reservoir or container 1 being filled, that the liquid fuel will begin to rise in the shell or casing 4' and upon reaching the underneath side of the float 35 will cause the same to be lifted with the gradual rise of the fuel until the cone valve 34 of the float 35 will become entirely seated in the seat 33 and as a result shut-off the further entrance of liquid fuel into the shell or casing 4' and the reservoir or container 1. By referring to Figure 1, the advantage of this action will be readily seen, due to the fact that if such a controlling means were not included with the reservoir or container 1 to determine the level at which the liquid fuel would rise when filling the reservoir or container, the liquid fuel would simultaneously rise in the supply line or pipe 6 which has connection with the reservoir 1 and overflow into the line or pipe 6' which would make the system ineffective for operation until the level of fuel in the reservoir or filling connections had been lowered preferably near or below the elevation of the L 7 in the supply line or pipe 6. The action of the float 35 within the shell or casing 4' is positive and effective and will be understood to prevent the liquid fuel from overflowing into the

supply fuel lines and starting a siphon by such overflow and emptying the reservoir or container 1 of its contents.

In the operation of the system, the reserve fuel tank 14 is first partially filled with liquid fuel, as shown in Figure 1 and at the same time the supply line or pipe 6" will be filled or primed to within a short distance of the suction and pressure pump 19. It is to be understood that once priming the supply fuel line 6", and the reserve fuel tank 14 to the approximate level shown in Figure 1, is all that is necessary, since the tank 14 always retains a quantity of liquid fuel when stopped at intervals caused by thermostatic control or by other means.

Assuming the reservoir or container 1 to contain fuel and the reserve fuel tank 14 primed with fuel and the supply line 6" filled with liquid fuel and the line 6' and 28 containing a volume of air, it will be readily understood that upon starting the pump 19, said pump will draw the liquid fuel from the line 6" and the tank 14. As the fuel in the tank 14 diminishes or is drawn from such tank it will start a siphonic action in the lines 28 and 6 and lift the fuel from the reservoir through the pipe 6 and down through the pipe 6' and into and through the tank 14 and into the fuel line 6". The unused or excess fuel being returned to the reservoir, under slight pressure, through the line 23, as will be understood.

Upon the cessation of the pump, it will be obvious that the fuel in the lines 6 and 6' will drain into the tank 14 and rise to the approximate point shown in Figure 1, forcing the air forward through the line 28 and into and through the line 6', breaking the siphonic action, previously described, due to the operation of the pump and stop the flow of fuel through the system; leaving the tank 14 and line 6" primed for further operation when the pump is again started. In other words, the rise and fall or movement of the fuel in the tank 14 will create, first a suction on the air in the lines 28 and 6 to start the siphoning of the fuel from the reservoir through the system, and as the pipes 6' and 6 drain into the tank 14 will supply the necessary pressure on the air in the air line 28 to fill the line 6' and break the siphonic action, thus created, and stop the flow of liquid until the pump is again started.

Figure 4 illustrates the approximate level at which the liquid fuel assumes when the pump 19 is in operation and the liquid fuel is in circulation in the fuel system. With the liquid fuel in circulation throughout the system, it is possible that quantities of air are drawn from the air pipe or line 28 into the line or pipe 6' at the T 10 with the liquid fuel and upon the air and fuel reaching the reserve fuel tank 14, it will be under-

stood that the air rises in the fuel and returns to the upper portion of the reserve fuel tank forming an air chamber and the air pipe or line 28.

What I claim is:—

1. In a liquid fuel burning system, in combination with a pressure means, fuel reservoir and supply and return fuel lines between said pressure means and said reservoir; a fuel supply tank in the supply line having priming means, and an air line in communication with said tank and the supply line between said tank and said reservoir; the operation of the pressure means diminishing the volume of the fuel in said fuel tank causing a displacement of the air in the supply line creating a siphon in said line and causing the flow of fuel from the reservoir to the pressure means, and the cessation of the pressure means recharging the fuel tank from the supply line, connecting said tank and reservoir, and breaking the siphon in said supply line by the admission of air therein expelled from said tank.

2. In a liquid fuel burning system, in combination with a pressure means and a reservoir; a filling regulator connected to the reservoir including an upstanding tubular container and a float valve therein adapted to close the inlet to the reservoir on the filling of the reservoir; supply and return fuel lines connecting said pressure means with said reservoir, the supply line including a section disposed in a plane above the cutting off inlet in said regulator; a fuel supply tank in the supply line having priming means, and an air line in communication with said tank and the supply line between said tank and said reservoir; the operation of the pressure means diminishing the volume of the fuel in said fuel tank causing a displacement of the air in the supply line creating a siphon in said line and causing the flow of fuel from the reservoir to the pressure means, and the cessation of the pressure means recharging the fuel tank from the supply line, connecting said tank and reservoir, and breaking the siphon in said supply line by the admission of air therein expelled from said tank.

3. In a liquid fuel burning system, in combination with a pressure means and a reservoir; supply and return fuel lines between said pressure means and said reservoir; controlling valves in both said supply and return fuel lines; a fuel tank in the supply line, the latter including a section discharging into said tank near its lower end and a section connected with its lower end to receive the flow of fuel therefrom; an air line in communication with the upper end of said tank and said first mentioned section of the supply line at a point between the tank and said reservoir, and a filling regulator for the reservoir having valve means operative

at a point below the connection between the air line and supply line; the operation of the pressure means diminishing the volume of the fuel in said fuel tank causing a displacement of the air in the supply line creating a siphon in said line and causing the flow of fuel from the reservoir to the pressure means, and the cessation of the pres-

sure means recharging the fuel tank from the supply line, connecting said tank and reservoir, and breaking the siphon in said supply line by the admission of air therein expelled from said tank.

In witness whereof, I have hereunto affixed my hand this 21st day of April, 1925.

LEPORT R. VAN SANT.
